Primary Examiner—B. J. Bullock*Attorney, Agent, or Firm*—Price, Heneveld, Cooper, De Witt & Litton[57] **CLAIM**

The ornamental design for an adjustable hanger body, as shown and described.

DESCRIPTION

FIG. 1 is a front, perspective view of an adjustable hanger body showing the new design;

FIG. 2 is a front, perspective view thereof with one arm telescoped into the central portion of the hanger body;

FIG. 3 is a fragmentary, right front elevational view thereof;

FIG. 4 is a fragmentary, right rear elevational view thereof;

FIG. 5 is a fragmentary, right top plan view thereof;

FIG. 6 is a fragmentary, right bottom view thereof;

FIG. 7 is a left end elevational view of a clamp shown separately for ease of illustration;

FIG. 8 is a front, perspective view of a second embodiment of the design of FIG. 1;

FIG. 9 is a front, perspective view of FIG. 8 with one arm telescoped into the central portion of the hanger body;

FIG. 10 is a fragmentary, right front elevational view of FIG. 8;

FIG. 11 is a fragmentary, right rear elevational view of FIG. 8;

FIG. 12 is a fragmentary, top plan view of FIG. 8;

FIG. 13 is a fragmentary, bottom plan view of FIG. 8; and,

FIG. 14 is a left end elevational view of a clamp shown separately for ease of illustration.

The hanger body is symmetrical about a vertical center line with the right view being a mirror image of the left view.

The clamps in FIGS. 1, 2, 8 and 9 are shown in the open position; all other views show the clamps in the closed position.
